UNITED STATES PATENT OFFICE.

WILLIAM F. HARRIS, OF GLOUCESTER, MASSACHUSETTS.

PURSING-SEINE.

SPECIFICATION forming part of Letters Patent No. 721,517, dated February 24, 1903.

Application filed November 1, 1902. Serial No. 129,650. (No model.)

To all whom it may concern:

Be it known that I, WILLIAM F. HARRIS, a citizen of the United States, and a resident of Gloucester, in the county of Essex and State 5 of Massachusetts, have made certain new and useful Improvements in Pursing-Seines, of which the following is a specification.

I have devised certain improvements in pursing-seines whereby great defects incident to the use of seines of the ordinary construction are overcome and highly important advantages attained.

In the accompanying drawings, three sheets, Figure 1 is a diagrammatic plan view illustrating the operation of my invention in practical use. Fig. 2 is a side view illustrating one stage of the operation of pursing the seine. Fig. 3 is a side view illustrating another stage in which the seine is completely pursed. Fig. 4 is a side elevation of a portion or a section of the seine, the same being shown extended vertically. Fig. 5 is a perspective view showing the seine in the position indicated in Fig. 3—that is to say, completely pursed. Fig. 6 is a diagrammatic plan view illustrating the operation of the seine. Fig. 7 is a view illustrating the attachment of the hauling and pursing line to the foot of the seine. Fig. 8 is a diagrammatic plan view illustrating the operation of the ordinary or old form of seine upon which mine 25 is an improvement.

The pursing-seines such as are used in the mackerel and menhaden fisheries are nets 35 ranging usually from nine hundred to fifteen hundred feet in length and from one hundred and sixty to one hundred and eighty feet in depth or width and are necessarily used in deep water. They are provided with floats 40 at the top and with heavy weights at the bottom, which are constructed in the form of rings weighing some five pounds each and serving as attachments and guides for the hauling and pursing rope or line. When such 45 rope is drawn in, the foot or weighted lower edge of the seine is drawn together or pursed, so that the entire seine forms a bag or pocket designed to surround and inclose the fish. In practice such seines are set out by the aid 50 of two boats, one a dory or small boat and the other a larger row-boat, in which the seine is

carried, the larger boat being rowed away from the dory in a great circle around the school or shoal of fish. The ends of the seine are finally brought together and attached to 55 the side of the row-boat. The boat's crew then haul in on the pursing line or rope, a winch being usually employed as an aid in this laborious operation. Owing chiefly to the resistance offered by the heavy metal 60 rings attached to the foot of the seine, the effect of the continued hauling and tension on the pursing-line is to draw the boat (see Fig. 8) toward the school of fish and forward 65 into the same or up to its edge, as there illustrated. The fish are thus frightened and seek every possible means of escape, one being to descend far enough to pass out under the net, while large numbers escape in the space beneath the boat. It is to avoid this 70 result, especially to prevent the boat being drawn over to or close to a school of fish, that I have devised my seine, whose construction and operation will now be described.

I dispense entirely with heavy weights or 75 guide-rings at the foot of the seine, and I construct the seine practically in two parts A B, (see Fig. 4)—that is to say, while the seine may be of the usual length it is divided lengthwise by a line or rope 1, which forms 80 the foot of the main portion or body A, which is also provided with floats 2^a at the top in the usual way. The foot-line 1 is provided with a series of small weights 2, which serve 85 in practice to carry down the part A and to hold it duly distended in the water, as indicated in Figs. 2, 3, and 5. The part B of the seine which depends from the foot-line 1 of the main portion A, I term the "pursing" portion, since its particular function is to gather 90 or draw in and also lift the part B, so as to close the bottom of the pocket formed by the seine, as indicated in Fig. 5. This pursing portion B is preferably constructed of lighter twine than the body portion A, and it is also 95 of slightly-greater depth or width. The hauling and pursing line 3 may be attached to the foot of the pursing portion B, as indicated in Figs. 4 and 7, it being adapted to slide in its attachments. In Fig. 4 the line 3 100 is shown passing slidably through small guide-rings attached to the foot of part B.

Any suitable guides may be employed for this purpose, and, if necessary, they may be weighted to a small degree. In Fig. 7 the pursing-line 3 is shown rove through the 5 lower edge of part B of the seine, so that the portion 5 of the seine is left entirely free on the pursing-line. The latter is attached permanently to the seine at 4. In both cases—to wit, in the arrangement shown in Fig. 4 10 and also that in Fig. 7—I prefer that the central portion of the foot of the pursing part B shall be left free, as thus indicated.

The seine is carried and paid out from a row-boat C (see Fig. 6) in the same manner 15 as seines of the usual construction, the buoy end of the seine being held or retained by a dory X, as indicated, while the boat C is rowed in a circle around a shoal Z of fish. As the row-boat proceeds the crew left in the 20 dory X begin to pull on the pursing-line 3, and thus begin to draw in or gather the pursing portion B of the seine at the very start. Consequently by the time the row-boat C has completed its circuit, as indicated in Fig. 25 1, the pursing portion B has been well drawn in around and under the school of fish Z. The ends of the seine being then attached in the usual way to the side of the boat C, the final operation of pursing the part B of the 30 seine instantly takes place—that is to say, the hauling and pursing line 3 is drawn upward and the part B of the seine is gathered and pursed and drawn upward so quickly that the fish are prevented from escaping in the 35 usual way. To accomplish this result in the most expeditious and economical manner, I employ a weight 6, (see Figs. 2 and 3,) which is attached to the free end of the hauling-line 3 and allowed to pass over the boat—that is 40 to say, so soon as the ends of the seine have been attached to the side of the boat, as before stated, the weight 6 is thrown over the opposite side of the boat and descending with great rapidity the line 3 applies great tractive and lifting force to the free portion B of the 45 seine, so that it is almost instantly gathered and drawn upward into the position shown in Fig. 3, whereby all escape of the fish is entirely cut off and they are pocketed, as will 50 be understood by reference to Fig. 5. It will be seen that in this operation the attachment of the pursing-line 3 to the foot of the pursing portion B of the seine is important, since the part 5 of the foot which intervenes, the 55 points 4 being left free, forms a loop 5, which is more easily hauled through the water than if the line 3 continued through the foot at the point 5, and practically when the loop thus formed is brought up, as indicated in Fig. 3, 60 the escape of the fish is effectually cut off. It will be seen that in the pursing operation the body A of the seine is but little disturbed or drawn out of its normal vertical position, since the tension of the pursing-rope 3 is 65 mainly on the lower, loose, and practically unweighted portion B of the seine, which being comparatively light and easily manipu-

lated may be gathered or pursed most expeditiously.

In order to facilitate a rapid descent of the 70 weight 6, attached to the pursing-line 3, and to prevent wear of the latter, I provide pulleys 7, (see Figs. 2 and 3,) which are journaled in arms or brackets attached to one of the thwarts of the boat C. Any convenient 75 arrangement of the pulleys may be employed, and it is practicable to entirely dispense with them and to allow the line 3 to run on the sides or gunwales of the boat. It is obvious 80 that the weight of the weight 6 may be varied 85 and that it will depend to a degree upon the depth or width of the seine and some other conditions. In any case its descent will be sufficient to effect the final step in the pursing operation with as much rapidity as practicable.

It will be seen that by reason of the rapid pursing of the seine, as well as the provision of the loose or lightly-weighted lower portion B, I avoid the disastrous result indicated in 90 Fig. 8—that is to say, the hauling of the boat to or into the school of fish. In brief, the comparative ease with which the pursing portion B may be hauled up and the inertia and 95 resistance of the boat with its broad side to the water are sufficient to prevent the boat moving laterally toward the opposite side or middle portion of the seine to any great extent at the time the weight 6 is let loose, so that the seine as a whole retains very nearly the circular form in which it is paid out of the row-boat, and the only effect of the hauling in and 100 pursing will be to draw the boat slightly toward the school Z of fish, whereby the circle may be reduced to an oval, as indicated in 105 Fig. 1. In any case a movement of the boat relative to the opposite middle portion of the seine is never sufficient to frighten the fish and endanger their capture, as with seines of 110 the usual construction.

Having thus described my invention, what I claim as new, and desire to secure by Letters Patent, is—

1. The improved pursing-seine having a body portion provided with floats at its upper 115 edge and small weights at its foot, a depending pursing portion, a hauling and pursing line connected with the foot of the pursing portion, and the weight attached to the free end of said line, substantially as shown and 120 described.

2. The improved pursing-seine comprising an upper or body portion having floats at its upper edge and a foot-line at its lower edge, and provided with a series of small weights 125 attached to said foot-line, and a free portion B which is pendent from the aforesaid body portion, and a pursing-line which is slidably connected with the middle part of the foot of the pursing portion B, and permanently attached at 4, that is to say at points intermediate of the middle part 5 and the ends of the pursing portion B.

3. The improved pursing-seine comprising

a body portion having weights attached to its lower edge, and a pursing portion which depends from the foot of such body portion and is constructed of twine of less size than that forming the body portion, and a pursing-line connected with the foot of such pendent pursing portion, substantially as shown and described.

4. The improved pursing-seine comprising a body portion having floats at its upper edge and a foot-line and weights at its lower edge, and the depending pursing portion which is made of lighter material and provided with a

haulng and pursing line at its foot, substantially as shown and described.

5. The fishing apparatus comprising a seine provided with a depending pursing portion and the hauling-line connected with the foot of the latter and having a weight attached to its free end, substantially as shown and described.
